UNITED STATES PATENT OFFICE.

MICHAEL LYNCH, OF PATERSON, NEW JERSEY.

STORING STRUCTURE.

1,242,012.

Specification of Letters Patent.

Patented Oct. 2, 1917.

Application filed March 27, 1916. Serial No. 87,030.

To all whom it may concern:

Be it known that I, MICHAEL LYNCH, a citizen of the United States, residing at Paterson, in the county of Passaic and State 5 of New Jersey, have invented certain new and useful Improvements in Storing Structures, of which the following is a specification.

This invention relates to structures for 10 the storing of coal, grain and the like materials. One object of the invention is to provide a storing structure in which various kinds or grades of material can be stored in a way facilitating their being selectively deposited in their appointed bins or compartments and their withdrawal therefrom in such manner as to avoid, as much as possible, interference with one another of the wagons or other vehicles which 15 come to the structure to be loaded; at the same time, the invention has for its further object to make the structure as strong, compact and durable as possible and also adapted to withstand the pressure of heavy loads 20 not always equally distributed in its several bins or compartments.

In the accompanying drawings,

Figure 1 is a side elevation of the improved structure;

30 Fig. 2 is a plan thereof, partly broken away;

Fig. 3 is a vertical sectional view of said structure on approximately the line $x-x$, Fig. 2;

35 Fig. 4 is a fragmentary sectional view on substantially the line y in Fig. 3 and on a somewhat larger scale; and,

Fig. 5 is a horizontal fragmentary sectional view through the lower part of the 40 cupola.

To support the bins or compartments of the improved structure I provide in the preferred construction a central column, pillar or pier a and a series of columns, pillars or 45 piers b arranged equidistantly from each other in a circle around the pillar or column a .

The column a , as herein shown, includes a reduced upper portion or extension c 50 around which are arranged, on the columns b , the aforesaid bins or compartments, which are built up as follows:

d denotes vertical walls radiating in equidistant relation to each other from the column-extension c , and in the preferred construction extending each to a greater dis-

tance from the column $a-c$ than is represented by the circle in which stand the columns b . These walls form the partitions between the several bins, whose outer walls 60 e join the walls d at their outer extremities, standing vertically. Forming the bottom of each bin are the walls f , g and h , walls g , h , sloping toward each other and all three walls all sloping toward the discharge outlet i of the bin, arranged half-way between the two corresponding columns b , wall f extending inwardly from the corresponding outer wall e and walls g h from the two partition walls d . Each outlet i preferably has 65 its bottom side i' a continuation of or flush with the bottom of the channel formed by the walls g h where they adjoin each other, and it may be equipped with a suitable form of chute j and a door or valve k operated 70 by hand from the outside.

Each bin is covered by the roof-wall or section l , these several walls abutting each other at their sides and at their outer extremities the vertical outer walls e ; they are 80 supported partly by being pitched upwardly toward a common center and abutting on each other and partly by the partition walls d , which, however, near the center of the structure extend short of said walls l , leaving 85 a clear space m above them. The walls l are surmounted by a cupola n having an opening p in one side and a central opening q in its floor in which is received the distributing hopper, to be described. 90

For strengthening the body of the structure, particularly against bulging under the pressure of its contents, I preferably provide a beam or girder r extending clear around the same on the inside and situated about 95 half-way of the height of each bin, its top surface being beveled, as shown.

The entire structure as so far described is preferably formed as an artificial monolithic body, being composed of concrete, reinforced by rods, bars or the like s , as best shown in Fig. 4. It is therefore exceedingly strong and compact, the bins not only having common support upon each other and on central column $a-c$, but support 100 also on the columns b , which are arranged well under the bins so as to assume the main portion of the load and at the same time allow the wagons or other vehicles to be loaded from the bins to stand, out of the 105 way of others passing around the structure, well under the same. By pitching each wall

f inwardly and downwardly and the walls *g* and *h* outwardly and downwardly to the circle represented by the pillars *b* and toward each other I not only cause the contents of each bin to fall, when released, toward the outlet *i*, but increase the strength of the structure in a way to reduce the mass of the underpinning afforded by the columns *b*.

10 The hopper aforesaid, denoted *t*, turns on a pivot *u* and roller bearings *v* on a plate *w* which surmounts the column *a—c*, and it has a spout *x* adapted to discharge into any particular bin on the hopper being 15 turned to bring the spout into register therewith. This is accomplished in the present instance by turning a vertical shaft *y* arranged to rotate in one of the walls *d*, having a handle *z* at its lower end and a 20 pinion 2 at its upper end meshing with a gear 3 on the hopper.

The coal or other material may be delivered from a railway siding 4 into the pit 5, and from there conducted up to and delivered into the hopper by the chain or other conveyer 6.

Having thus fully described my invention, what I claim is:

1. A storing structure consisting of a 30 series of substantially triangular bins arranged around a common vertical axis and each laterally abutting on two other bins in

said series, and spaced columns supporting said series of bins and arranged around and in substantially a circle concentric with 35 said axis and appreciably less in diameter than the series of bins, each bin having an outer bottom wall sloping inwardly and downwardly, and inner bottom walls sloping outwardly and downwardly, toward and 40 meeting at said circle, the said inner bottom walls also sloping toward each other, and each bin having an outlet at substantially where the bottom walls thereof meet.

2. A storing structure consisting of a 45 series of substantially triangular bins arranged around a common vertical axis and each laterally abutting on two other bins in said series, and spaced columns supporting said series of bins and arranged around 50 and in substantially a circle concentric with said axis and appreciably less in diameter than the series of bins, each bin having an outer bottom wall sloping inwardly and downwardly, and inner bottom walls sloping outwardly and downwardly, toward and 55 meeting at said circle, the said inner bottom walls also sloping toward each other, and each bin having an outlet in its outer bottom wall at the juncture of said wall 60 with the two inner bottom walls.

In testimony whereof I affix my signature.

MICHAEL LYNCH.
